AUTOMATIC CONTROL FOR LETOFF
MECHANISM OF LOOMS

Yervant H. Kurkjian, Clifton, N. J.

Application September 28, 1943, Serial No. 504,180

1 Claim. (Cl. 139—107)

This invention relates to an automatic control for let-off mechanism of looms, and the like, and has for one of its objects the production of a simple and efficient automatic let-off control which will control the tension of the brake band of the warp beam in a proper manner to maintain a uniform tension of the warp threads carried by the warp beam.

A further object of this invention is the production of a simple and efficient means for controlling the tension of the brake band of the warp beam of a loom, wherein the control means is located below and extends longitudinally of the beam in one form illustrated.

Other objects and advantages of the present invention will appear throughout the following specification and claim.

In the drawing—

Figure 1 is a fragmentary front elevational view of the automatic let-off control;

Figure 2 is a fragmentary sectional view taken on line 2—2 of Figure 1;

Figure 3 is an end elevational view of a modified form of the invention.

By referring to the drawing, it will be seen that 10 designates the supporting frame upon which is mounted in any conventional way, a conventional warp-supporting beam 11. The warp 12 is wound upon the beam 11 in the usual manner. A brake drum 13 is carried by the beam 11, and a brake band 14 is anchored, as at 15, at one end to the frame 10. The brake band 14 is secured at its opposite end, as at 16, to the brake lever 17. The brake lever 17 is pivoted to the frame 10 by means of a pivot 18, and carries, at its opposite end, a pivoted depending link 19, as shown in Figure 1. This link 19 is pivotally connected to the inner end 20 of a weight or tension lever 21, which lever 21 is pivotally supported upon the frame 10 by a pivot 22.

A weight 23 is adjustably mounted in a selected position upon the weight lever 21, and a spring-pressed contact roller 24 is carried by a bracket 25, which is in turn pivotally carried, as at 26, upon the lever 21. This roller 24 contacts with the warp 12 in the manner shown in Figures 1 and 2, and is firmly held in this contacting position by means of the spring 27. As the warp 12 is unwound from the beam 11, the roller 24 will move inwardly toward the beam 11 to the dotted line position shown in Figure 1, thereby reducing the pressure upon the weight beam 21 and also reducing the tension of the brake band 14 upon the brake drum 13 in a manner similar to that described in my application Serial Number 477,743. As this tension is reduced, the brake band 14 will be loosened due to the reduction of

pressure upon the lever 21. Consequently, as the warp is unwound from the beam, the brake band will be loosened so as to maintain at all times a substantially uniform tension upon the warp. The tension of the brake band 14 will be regulated in ratio to the unwinding of the warp, the position of the roller 24 shifting automatically as the diameter of the warp reduces.

In Figure 3, there is shown a modification of 10 the invention, wherein the control is mounted at the end of the frame 10a. The warp supporting beam 11a is carried above the frame 10a as shown, and the warp 12a is carried by the beam 11a. A brake drum 13a is also carried by the beam 11a and a brake band 14a is secured at one end to the frame 10a, as at 15a, and at its opposite end, as at 16a to the brake lever 17a. This lever 17a is pivoted to the frame 10a, as at 18a, and supports at its inner end a pivoted link 19a. The link 19a is pivoted to the inner end 20a of a tension lever 21a, the lever 21a being pivoted as at 22a to the frame 10a.

The tension lever 21a is connected at its outer end to a depending tension spring 27a and the opposite end of the spring 27a is connected to a crank arm 26a of the warp-engaging bell crank lever 25a. The lever 25a carries a roller 24a which contacts the warp 12a wound upon the beam 11a and as the warp is unwound the lever 25a will swing toward the warp in the direction of the arrow and relieve the tension on the spring 27a, the lever 21a, the lever 17a, and the brake band 14a. Consequently, the tension of the warp will, in this manner, be automatically kept substantially uniform at all times.

Having described the invention, what I claim is:

An automatic let-off control of the class described comprising a support, a beam carried by the support, a warp wound upon the beam, a 40 brake drum carried by the beam, a brake band passing over the drum, a brake lever mounted adjacent the drum, the brake band engaging one end of the brake lever, a pivot supporting the brake lever, a tension lever pivoted to said support, a link connecting the adjoining end of said tension lever to the adjoining end of said brake lever, a depending tension spring connected to the opposite end of the tension lever, a bell crank warp-engaging lever pivoted to the frame, said 45 warp-engaging lever having at one end a warp contacting means, and at its other end a crank arm engaging said tension spring for maintaining a substantially uniform tension upon the warp at all times and for regulating the pull upon the 50 brake band as said warp unwinds from the beam.

YERVANT H. KURKJIAN.
